THROTTLE PUMP CARBURETOR

Filed July 5, 1924

UNITED STATES PATENT OFFICE

CHARLES H. KIRBY, OF FLINT, MICHIGAN, ASSIGNOR TO "MARVEL CARBURETER COMPANY," OF FLINT, MICHIGAN, A CORPORATION OF INDIANA

THROTTLE-PUMP CARBURETOR

Application filed July 5, 1924. Serial No. 724,230.

This invention relates to a pumping type high speed nozzle for carburetors wherein the sudden opening of the throttle serves to give an injection of fuel in addition to the normal supply thereof.

It is an object of this invention to provide a throttle pump of the class described wherein the pump will respond to abnormal demands on the carburetor while being non-responsive to the ordinary requirements of average operation. To accomplish this object a lost motion connection is provided whereby a predetermined movement of the throttle occurs before the pump or injector becomes operative. This movement of the throttle preferably covers the power requirements for the normal range of driving conditions for an automobile on the level. Within this driving range an injector or pump is not ordinarily required by the average automobile engine, although of course it is within the scope of this invention to provide any degree of responsiveness of the pump to throttle movement for the special requirements of particular services.

It is another object of this invention to combine such a throttle pump with a metering pin that normally limits the flow of fuel to the high speed nozzle of a carburetor under the normal range of operating conditions, while when the pump is brought into action the metering pin will enlarge the fuel passage to meet the abnormal requirements of the engine.

It is also an object of this invention to provide an improved throttle pump wherein the pump is inoperative except for sudden operation of the throttle, as when quick acceleration in traffic is required.

Other and further important objects of this invention will be apparent from the disclosures in the drawings and specification.

The invention (in a preferred form) is illustrated in the drawings and hereinafter more fully described.

On the drawings:

Figure 1 is a vertical elevation of a carburetor with parts broken away to show the application of the device of this invention applied thereto.

Figure 2 is a fragmentary section through the fuel pump.

As shown on the drawings:

The carburetor chosen for illustration comprises a float chamber 5 having an outlet 6 in a boss 7 which will be referred to in detail later. Adjacent the float chamber is the casting 8 of the mixing chamber, having a flap air valve 9 arranged on a pivot 10 intersecting the axis of the chamber. This valve is cut away as at 11 so as not to interfere with the high speed nozzle 12 which is fed from the outlet 6 by way of the chamber 13 and cored passage 14. Also arranged in the mixing chamber is a low speed venturi 15 and needle 16 controlled nozzle 17. The usual air inlet passage 18 and choker valve 19 are shown. The end of the throttle shaft is indicated at 20. The throttle lever 21 is double ended of bell crank form, one end 22 carrying an adjustable stop screw 23 for idling adjustment, and the other end serving as a stop defining the wide open position.

The pump of this invention comprises a pump casing 24 formed as part of the carburetor body and including the chamber 13 as an enlargement of the main bore 25, which contains a piston 26 normally held up by a coil spring 27 which seats on a plug 28 between the chamber 13 and the bore 25. This plug is provided with a restricted orifice 29 which is normally restricted by a metering pin 30 dependent from the piston 26. The pin 30 is tapered off to a small diameter for the central part of its length to enlarge the orifice when the piston is forced downwardly.

The pump bore is maintained full of fuel by the float chamber the outlet 6 of which opens into a horizontal passage 31 which intersects the bore 25. The end of this passage is provided with a tapered seat 32 for a ball check valve or suction valve 33, the ball being retained in place by an inserted pin 34. Due to the horizontal arrangement of the passage the ball tends to roll away from the valve seat 32, and a substantial pressure will be required to lift the ball valve up the incline to its seat. The angle of this seat therefore determined the relative quickness of operation of the pump to effect discharge

through the orifice 29 by first seating the ball 33 to prevent backflow into the float chamber.

The angle of the seat 32 can be altered to suit the acceleration requirements of different designs of engines. For example, with some engines it is not necessary to provide an excess of fuel for a comparatively slow acceleration of the throttle, while in others, due to manifold size and valve timing, it is necessary to accelerate the flow of fuel for practically any degree of throttle acceleration to secure equal performance comparative with the first type of engine. In practice the required angle for a particular design of engine is easily established, it being unnecessary to vary the angle for individual motors of the same design.

The pump piston is actuated by a plunger 35 which has a pivoted connection 36 with the arm 22 of the throttle lever as indicated at 37. The end of the plunger is spaced from the piston when the throttle mechanism is closed by an amount determined by the desired range of normal operation without the pump, thus giving a lost motion connection that results in reserving the pump for abnormal sudden demands of the carburetor, such as is required in rapid acceleration.

The operation of this device as a pump is confined to sudden movements of the throttle mechanism which imparts sufficient energy to the fuel below the piston to close the ball valve 33. On the other hand, the metering pin serves to supply more fuel to the nozzle under conditions of continued abnormal demand such as for hill climbing where the initial pump injection is exhausted before the power demands drop back to normal.

The metering pin opens up the fuel passage to give an over-supply of fuel. Therefore the relative point of opening, determined by the position of the enlarged diameter of the metering pin can be altered to provide excess fuel above any desired operating range to suit particular conditions of service or the requirements of particular engine designs.

I am aware that numerous details of construction may be varied through a wide range without departing from the principles of this invention, and I therefore do not purpose limiting the patent granted otherwise than necessitated by the prior art.

I claim as my invention:

1. In a carburetor including a throttle and a float chamber, a fuel pump operatively connected to the throttle and drawing fuel from the float chamber, and a lost motion in said operating connection to the throttle whereby the pump is not brought into action until after a predetermined movement of the throttle.

2. A throttle pump comprising a spring restrained piston, a plunger connected to the

throttle and making a delayed contact with the piston to force the piston inwardly against the spring during the latter part of the stroke of the plunger, and a spraying nozzle connected to said pump.

3. A throttle pump comprising a spring restrained piston, a plunger connected to the throttle and making a delayed contact with the piston to force the piston inwardly against the spring during the latter part of the stroke of the plunger, and means adapted to render the pump ineffective during slow movements of the throttle.

4. A throttle pump comprising a spring restrained piston, a plunger connected to the throttle and making a delayed contact with the piston to force the piston inwardly against the spring during the latter part of the stroke of the plunger, and an apertured plug forming an orifice outlet from said pump, and a metering pin attached to said piston and adapted to vary the area of said orifice.

5. In a carburetor, a throttle operated pump having a delayed action connection with the throttle, and a metering pin in connection with the pump discharge adapted to normally permit a restricted flow of fuel past the pump and to increase the flow of fuel upon actuation of the pump.

6. In a carburetor including a throttle and a float chamber, a fuel pump operatively connected to the throttle and supplied with fuel through a passage communicating with the float chamber, and means in said communicating passage adapted to allow return of the fuel in the pump to said float chamber upon a slow opening of the throttle, but preventing this return upon a predetermined degree of rapid opening of the throttle.

7. In a carburetor including a float chamber, a throttle actuated fuel pump having a discharge nozzle and a fuel intake passage communicating with the float chamber, and a ball valve and seat therefor in said passage, the passage having an inclined surface upon which the ball is movable upwardly onto said seat, whereby it will only be seated when the pump is actuated with sufficient speed to force the ball up the incline and will otherwise permit of return flow from the pump to the float chamber.

8. In a carburetor including a throttle and a float chamber, a fuel pump operatively connected to the throttle and drawing fuel from the float chamber, and means in said operating connection to the throttle whereby the pump is not brought into action except at the end of the normal range of opening of the throttle.

In testimony whereof I have hereunto subscribed my name.

CHARLES H. KIRBY.
